UNITED STATES PATENT OFFICE.

EDWARD J. RENNER, OF SWISSVALE, PENNSYLVANIA.

PLAYTHING FOR CHILDREN.

1,303,392.

Specification of Letters Patent. Patented May 13, 1919.

Application filed January 10, 1919. Serial No. 270,481.

To all whom it may concern:

Be it known that I, EDWARD J. RENNER, a citizen of the United States, residing at Swissvale, in the county of Allegheny and 5 State of Pennsylvania, have invented certain new and useful Improvements in Playthings for Children, of which the following is a specification.

My invention relates to children's playthings, and has for an object the provision of a wheelbarrow body which may be removably attached to the well-known "kiddie kar", whereby the latter may be converted into a toy wheelbarrow at will.

15 I will describe one form of plaything embodying my invention, and will then point out the novel features thereof in claims.

In the accompanying drawings, Figure 1 is a view showing in side elevation one form 20 of plaything embodying my invention, the wheelbarrow body being in place on, and attached to, the car. Fig. 2 is a sectional view on the line II—II of Fig. 1, showing part of the means for holding the wheelbarrow body 25 in place on the platform of the car. Fig. 3 is a sectional view on the line III—III of Fig. 1, showing the remainder of the means for holding the wheel-barrow body in place on the car, and also showing means for holding the steering post fixed in position when the wheel-barrow body is on the car. Fig. 4 is a view on a larger scale than the preceding 30 views and showing in more detail the hook for attaching the wheelbarrow body to the 35 steering post of the car.

Similar reference characters refer to similar parts in each of the views.

Referring first to Figs. 1, 2 and 3, the car comprises, as usual, a platform 1. Attached 40 to this platform on its underside and near the rear end is a suitable block 2 in which the rear wheels 3, 3 are journaled. Near its forward end the platform is provided with a hole through which passes the steering post 4. The lower end of the steering post is 45 bifurcated to receive the front wheel 5, and the upper end is provided with the usual laterally projecting handle bars 6. The part of this post above the platform 1 is preferably 50 square in cross section, as shown in Fig. 3, for a reason which will appear hereinafter.

The wheelbarrow body comprises a floor piece 7, two side pieces 8, 8, an end piece 9 and two handles 10, 10. The handles are 55 attached to the underside of the floor piece 7, and are so spaced that the platform 1 of the

car may be passed in between them with a snug but sliding fit. When the wheelbarrow body rests on the platform of the car with the platform between the handles, then these handles serve to prevent lateral movement of the body with respect to the car. In order to prevent the body from rising vertically from the platform, each handle is provided with a horizontal plate 11 extending inwardly from 60 the handle, so that these plates lie under the platform, as shown in Fig. 2 when the body is in place on the car.

When the combined device is to be used as a wheel-barrow, it is obvious that the steering 65 post 4 must be prevented from turning. To accomplish this, the floor piece 7 of the wheelbarrow body is provided with two forwardly projecting ears 7^a, 7^a, which rest on opposite sides of the steering post and so lock the latter in such position that the front wheel 5 is 70 parallel to the longitudinal axis of the car.

To hold the wheelbarrow body in proper longitudinal position on the car, means are provided for attaching the body to some 75 part of the car and preferably to the steering post 4. As here shown, this means comprises an ordinary hook 12 (see Fig. 4) which is attached to the front end of one ear 7^a by a screw eye 13, and which is 80 adapted to enter a similar screw eye 14 in the front end of the other ear 7^a. It will be seen that when this hook is in place no backward movement of the wheelbarrow body with respect to the car can occur.

When it is desired to remove the wheelbarrow body from the car, it is only necessary to withdraw the hook 12 from its screw eye 14 and slide the body backward with respect to the car. Replacement of the body 95 is accomplished by a similar but reverse sequence of operations.

Although I have herein shown and described only one form of plaything embodying my invention, it is understood that various changes and modifications may be made therein within the scope of the appended 100 claims without departing from the spirit and scope of my invention.

Having thus described my invention, 105 what I claim is:

1. A plaything for children comprising a kiddie car, a toy wheelbarrow body, and means for removably attaching said wheelbarrow body to said car.

2. A plaything for children comprising a kiddie car, a toy wheelbarrow body, and

means for removably attaching said body to the platform and to the steering post of said car.

3. A plaything for children comprising a kiddie car, a toy wheelbarrow body, guides on the under surface of said body arranged to slide along the edges and under surface of the platform of said car for preventing lateral and vertical movement of the body with respect to the car, and means for preventing longitudinal movement of said body with respect to said car.

4. A plaything for children comprising a kiddie car having a steering post, the portion of said post which is above the platform of the car having two parallel flat sides, a wheelbarrow body, and two for-

wardly projecting ears on said body arranged to coat with the flat sides of said post to hold the front wheel of the car 20 parallel to the longitudinal axis of the car.

5. A plaything for children comprising a kiddie car, a toy wheelbarrow body, and means associated with said body and coating with the steering post of the car to hold 25 the front wheel of the car parallel to the longitudinal axis of the car.

In testimony whereof I affix my signature in presence of two witnesses.

EDWARD J. RENNER.
